UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

CLOSURE FOR SIFTER-TOP CANS.

Application filed November 10, 1923. Serial No. 674,064.

My invention relates to closures for talcum powder cans, its main object being the provision of a closure which will effectively close the sifter openings by very simple closing operation and which is adapted to be formed economically by reason of the ease of the manufacturing operations required.

Other objects and advantages of the invention will be apparent as it is better understood from the following description, which, taken in connection with the accompanying drawings, discloses a preferred embodiment thereof.

Referring to the drawings,

Figure 1 is a side elevation of a container in which my invention is embodied, the cap being shown in separated relationship;

Fig. 2 is a top plan view thereof with the cap removed; and

Fig. 3 is an enlarged side elevation, a part thereof being broken away and shown in section for convenience in illustration.

The container body 11 may be of any preferred form, being shown, however, as of the oblong shape now commonly in use. A top

12 is provided with a depending flange 13 engaging over the top of the body and held in place by friction, or by any desired form of connection. A neck 14 is secured in a

30 circular opening in the central part of the top 12, the connection, in the present instance, being provided by means of a shoulder 15 on the exterior of said top and a flange (not shown) crimped against the interior of the top about said opening. Sifter openings 16 are formed in the top of said neck in any desired number or arrangement.

40 A removable cap 17 is provided to close the sifter openings and a sealing disk 18 of felt, or the like, is seated in the top of said cap.

As a means of tightening said cap upon the neck 14, I provide interrupted threads

19 struck outwardly from the wall of said neck and embossed points 21 struck inwardly at intervals in the wall 22 of said cap. The threads 19 are inclined from the horizontal, and upon the cap being positioned with the points 21 between the threads 19 and rotated, it is forced downwardly until the liner 18 is tightly held upon the top of the neck, thus effectively closing the sifter opening. The threads 19 and embossed points 21, of course, may be easily formed by merely pressing the metal in the manner indicated and the cost of production is, therefore, very small.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

A closure for talcum powder cans, comprising a sheet metal neck part having a rounded top provided with sifter openings therein and with interrupted inclined threads bent outwardly from the cylindrical wall of said neck, an imperforate cap having a rounded top conforming with said top of the neck and rounded downward closely over the edge of the neck and thence bulged outward and thence bent inward to form a securing flange close to the neck, and inwardly extending embossments on said flange adapted to engage under said threads of the neck, and a sealing disk tightly and permanently confined in the cap under the top thereof.

JOHN M. HOTHERSALL.
